PICTURE HANGER

Halbert Lynn White, Kansas City, Mo.

Application January 17, 1949, Serial No. 71,277

2 Claims. (Cl. 248—31)

1

This invention relates to hangers and particularly to structure for mounting a picture, mirror, plaque and the like, the primary object being to provide a hanger for supporting the article to be hung in a straight, untilted condition at all times.

The most important object of the present invention is the provision of a picture hanger having a pair of elongated, interconnected arms extending in opposite directions and having hooks provided on the outermost ends thereof for receiving the usual picture cable or other bracket on the picture, thereby presenting a two-point support, serving to prevent tilting.

Another important object of the present invention is to provide a picture hanger having the aforesaid hooked arms and a member at the point of interconnection between the arms adapted for mounting upon a vertical wall, said member being provided with means for adjusting the arms in a number of directions to positively align the picture supported by the hanger.

Other objects of the present invention include the way in which the arm hooks are formed to prevent slippage between the picture-suspending means and the hanger, per se; the way in which a slot is provided in the arms for receiving a screw, permitting vertical adjustment of the bracket; the manner in which the arms are swingable about the said screw; and the way in which the arm support is itself mounted upon a wall in such manner as to prevent displacement thereof in any direction;

In the drawing,

Fig. 1 is a front elevational view of a picture hanger made in accordance with the present invention, showing the same in operative use on one form of picture-suspending means.

Fig. 2 is a top plan view thereof.

Fig. 3 is a transverse, cross sectional view taken on line III—III of Fig. 1.

Fig. 4 is a rear elevational view showing the side of the bracket opposite to that illustrated in Fig. 1; and,

Fig. 5 is a view similar to Fig. 4, showing the bracket in use with a modified form of picture-suspending means.

The picture hanger forming the subject matter hereof includes a pair of sections 10 and 12, both formed from an initially flat sheet of material, preferably metallic. Section 12 of the bracket is formed to present a pair of oppositely-extending, interconnected arms 14 and 16 of identical character, there being a slot 18 provided in the

2

section 12 at the point of merger between the proximal ends of arms 14 and 16.

Each arm 14 and 16 is provided with a hook 20 at the outermost, free end thereof, said hooks 20 being bent laterally in a direction away from the section 10 when the two sections are interconnected. As noted in Fig. 2, the hooks 20 diverge as the outermost edges thereof are approached.

Fig. 2, also, illustrates the way in which the two arms 14 and 16 are curved slightly from their point of interconnection toward the section 10 as the hooks 20 thereof are approached. Each of the hooks 20 is provided with a V-shaped notch 22, the apex of the notches 22 being at the innermost ends thereof.

The section 10 comprises a relatively small plate having a lateral flange 24 at the normally lowermost edge thereof and a flange 26 at its uppermost edge extending in the same direction as flange 24 and provided with a pair of spaced, pointed ears 28. The flange 26 of section 10 is, also, provided with a down-turned tab 30 that is perforated at 32 for receiving a nail or other fastening element 34.

As is clear in Fig. 3 of the drawing, the nail 34 also passes through an opening 36 formed in the section 10 immediately below the laterally-turned flange 26. A screw 38 threaded into the section 10 just above the flange 24 has a head provided with a diameter that is greater than the width of the slot 18, said screw 38 being disposed within the slot 18 and freely slidable therein when screw 38 is loosened with respect to section 10.

In Figs. 1 to 4, inclusive, there is illustrated a bracket 40 constituting an elongated strip having offset ends 42 secured to the back of a picture 44 through suitable fastening elements 46. The offset portions 42 of the strip 40 serve to hold the latter in spaced relationship to the back of the picture 44, as shown in Fig. 2. The bracket 40 is designed to fit into both of the hooks 20 of section 12 by spanning the distance therebetween when the bracket is placed in use.

Fig. 5 in the drawing illustrates a conventional cord 48 mounted on the back of a picture 50 through the medium of a pair of spaced eye screws 52 or the like in the usual manner. This picture-suspending cord 48 is, also, adapted to be looped over the two hooks 20 in much the same manner as the bracket 40.

When the picture hanger is placed in use, the supporting section 10 is fastened to a vertical wall 54 through the medium of the nail 34. It

is to be noted that the openings 32 and 36 are so disposed as to hold nail 34 at an angle with respect to the wall 54, thereby assuring that the weight of the picture will not pull nail 34 from its driven position in wall 54.

When nail 34 is driven in place, the pointed ears 28 of section 10 will, also, be embedded a short distance in wall 54, as limited by the tab 30. The downward angle of the ears 28 is slightly less than the angle of nail 34; and, through such construction, it has been found that mutilation of the surface of wall 54 will be minimized.

Furthermore, the difference in the inclinations of nail 34 and ears 28 serves to prevent a chipping away of wall 54 by the ears 28 that would tend to prevent the holding action which ears 28 provide.

When the section 10 is mounted upon the wall 54 in the manner just described, the flange 24 will hold the section 10 substantially vertical and spaced away from wall 54 to provide clearance for the innermost end of screw 38.

In the event that the longitudinal axis of section 10 is not truly vertical after the same is mounted upon wall 54, the picture can, nevertheless, be aligned properly by loosening of the screw 38, permitting free, swinging movement of arms 14 and 16 on the substantially horizontal axis of screw 38.

Furthermore, the arms 14 and 16 can be raised or lowered with respect to section 10 by reason of the slot 18 and screw 38, whereupon the screw 38 may be tightened for holding sections 10 and 12 relatively immovable. To further assure that section 12 will not slip with respect to section 10, the proximal surfaces of these sections are roughened as at 56 and 58.

The bracket 40 can be adjusted to the point desired within the notches 22; and, when so positioned, bracket 40 will rest within the V-shaped notches 22 and bind itself against sliding movement relative to the hooks 20. By the same token, the picture 50 can be swung to a positively aligned position and the cable 48 will be tightly gripped by the notches 22 of ears 20.

It is, also, to be noted, particularly in the form of the invention shown in Figs. 1 to 4, inclusive, that the picture can be adjusted horizontally. The bracket 40 will slide in the V-shaped notches 22 when bracket 40 is lifted slightly; and, therefore, the picture can be positioned as desired. This is of importance when a number of relatively small pictures are grouped together on a wall and where it is desired to space such pictures properly, even though in driving the nails, the user may not attain such perfect spacing.

Through the longitudinal bend of the arms 14 and 16 rearwardly toward the wall 54, as shown in Fig. 2, the picture 44 can be disposed relatively close to the surface of wall 54. A second tapped opening 60 is provided in the section 10, just above the opening receiving screw 38, to receive a second screw much like screw 38, when the section 12 is moved upwardly toward the nail 34 to a position where screw 38 would likely loosen and permit the picture to tilt out of alignment.

It is appreciated that the picture hanger just described is exceptionally simple and inexpensive to manufacture, easily mounted and adjusted and capable of maintaining a picture or other similar object in positive alignment at all times. Details of construction can, of course, be varied within the broad scope of the invention; and, therefore, such changes and modifications as fairly come within the spirit of this invention as defined by the scope of the appended claims are contemplated hereby.

Having thus described my invention, what I claim as new and desire to secure by Letters Patent is:

15. For a picture, a hanger comprising an elongated, horizontal member adapted for attachment to the back of the picture; a pair of plate-like sections, one of the sections being elongated, longitudinally arched, presenting a rearmost concave face and a forwardmost convex face, and having a central portion provided with a vertical slot and a pair of integral, oppositely extending arms projecting upwardly and outwardly from the central portion; a forwardly-extending hook on the outermost free end of each arm respectively, said hooks converging as the arms are approached and each being provided with an upwardly opening, V-shaped notch receiving said member, the other section having an opening for receiving a rearwardly-extending fastening element; and horizontal screw means in said slot attached to the other section and slidably and rotatably interconnecting the sections, the other section having a forwardmost vertical face engaging the central portion of the one section on the rearmost concave face of the latter, said other section having a pair of rearwardly-extending flanges, one of the flanges having a plurality of wall-piercing ears thereon.
20. The invention, as set forth in claim 1, wherein in the said interengaging faces of the two sections are roughened whereby, when said screw means is manipulated to clamp the sections together, the sections will not rotate or slide relatively.
25. The invention, as set forth in claim 1, wherein in the said interengaging faces of the two sections are roughened whereby, when said screw means is manipulated to clamp the sections together, the sections will not rotate or slide relatively.
30. The invention, as set forth in claim 1, wherein in the said interengaging faces of the two sections are roughened whereby, when said screw means is manipulated to clamp the sections together, the sections will not rotate or slide relatively.
35. The invention, as set forth in claim 1, wherein in the said interengaging faces of the two sections are roughened whereby, when said screw means is manipulated to clamp the sections together, the sections will not rotate or slide relatively.
40. The invention, as set forth in claim 1, wherein in the said interengaging faces of the two sections are roughened whereby, when said screw means is manipulated to clamp the sections together, the sections will not rotate or slide relatively.
45. The invention, as set forth in claim 1, wherein in the said interengaging faces of the two sections are roughened whereby, when said screw means is manipulated to clamp the sections together, the sections will not rotate or slide relatively.

HALBERT LYNN WHITE.
